(57) CLAIM

The ornamental design for an oven, as shown and described.

DESCRIPTION

The patent or application file contains at least one drawing executed in color. Copies of this patent or patent application publication with color drawing(s) will be provided by the Office upon request and payment of the necessary fee.

FIG. 1 is a front perspective view of a first embodiment of our new design for an oven;

FIG. 2 is a left-side elevation view thereof;

FIG. 3 is a right-side elevation view thereof;

FIG. 4 is a top plan view thereof;

FIG. 5 is a bottom plan view thereof;

FIG. 6 is a front elevation view thereof;

FIG. 7 is a rear elevation view thereof;

FIG. 8 is a bottom plan view thereof, shown with legs folded in a closed configuration;

FIG. 9 is another front perspective view thereof, shown with legs unfolded in an open configuration;

FIG. 10 is a front perspective view of a second embodiment of our new design for an oven;

FIG. 11 is a left-side elevation view thereof;

FIG. 12 is a right-side elevation view thereof;

FIG. 13 is a top plan view thereof;

FIG. 14 is a bottom plan view thereof;

FIG. 15 is a front elevation view thereof;

FIG. 16 is a rear elevation view thereof;

FIG. 17 is another front perspective view thereof;

FIG. 18 is a front perspective view of a third embodiment of our new design for an oven;

FIG. 19 is a left-side elevation view thereof;

FIG. 20 is a right-side elevation view thereof;

FIG. 21 is a top plan view thereof;

FIG. 22 is a bottom plan view thereof;

FIG. 23 is a front elevation view thereof;

FIG. 24 is a rear elevation view thereof; and,

FIG. 25 is another front perspective view thereof.

The portions of the oven shown in broken line form no part of the claimed design.

1 Claim, 25 Drawing Sheets
